CLAIM

The ornamental design for a plastic deep electrical junction box, as shown and described.

DESCRIPTION

FIG. 1 is a top plan view for a plastic deep electrical junction box, showing our new design;

FIG. 2 is a bottom plan view thereof;

FIG. 3 is a rear elevation view thereof, the front elevation view being a mirror image thereof;

FIG. 4 is a right-side elevation view thereof;

FIG. 5 is a top, rear, right-side perspective view thereof; and, FIG. 6 is a bottom, front, left-side perspective view thereof. The dash-dash broken lines in the drawings are for the purpose of illustrating portions of the plastic deep electrical junction box that form no part of the claimed design. The dot-dash-dot broken lines in the drawings are for the purpose of defining the bounds of the claimed design.
